UNITED STATES PATENT OFFICE.

ISAAC M. ROSS AND JOSEPH W. ROSS, OF SOUTH CARROLLTON, KY.

COMBINED BAIL-EAR AND LOCK.

SPECIFICATION forming part of Letters Patent No. 275,416, dated April 10, 1883.

Application filed November 6, 1882. (Model.)

To all whom it may concern:

Be it known that we, ISAAC M. ROSS and JOSEPH W. ROSS, of the town of South Carrollton, in the county of Muhlenburgh and State 5 of Kentucky, have invented a new and useful Improvement in a Combined Bail-Ear and Lock, which improvement is fully set forth in the following specification, reference being had to the accompanying drawings.

This invention has relation to improvements in bail-ears; and it consists in the novel construction and arrangement of the same, whereby the lid may be locked to a pail or vessel, thus protecting the contents therein, all as 15 will be hereinafter more fully explained.

The annexed drawings, to which reference is made, fully illustrate our invention, in which Figure 1 represents a perspective view of a pail, showing our device attached thereto; and 20 Fig. 2 is a similar view, showing our device in a modified form.

Referring by letter to the accompanying drawings, J designates a pail or vessel, L the lid or cover, and N the bail by which the same 25 is carried, all being of ordinary construction.

A indicates a bail-ear, hinged at C to a plate, G, that is secured to the side of the pail J.

Above the hinge-joint C the ear is provided with a casing, e, having in its outer face a key-hole, d, and on the inside thereof a hook, e, 30 that is operated upon by a key, f, in locking and unlocking the ear.

In the inner face of the upper portion of the ear is a slot, b, that opens into the lock-casing e, through which passes the free end of a link, B, that is hinged at d' to the handle e' of the cup M. Above said slot is an eye, H, made in the ear, in which the hook end of the bail N is attached. Opposite the lock-ear, and 35 secured to the opposite side of the pail, is a stationary ear, K, having an eye, f', for the opposite hook end of the bail, and below said eye this ear is provided with a perforation, a, through which passes the outer end of a pin, 40 D, that is secured at its inner end to the lid or cover L.

Fig. 2 of the drawings shows our device in a modified form, having the slot b and eye H, but no lock-casing, and this ear is connected 45 or hinged at its lower end, E, to a bar, I, that is secured at its ends h h to the pail.

The free end of the loop P in Fig. 2 connects with the ear R through the slot b, similar to Fig. 1, and the construction is the same, 50 except that the inner end of said loop is not

hinged to the cup-handle, but is hinged to a plate, i, that is secured to the upper face of the lid L.

It will thus be seen by the above description, and by reference to the drawings, that 55 when it is desired to secure the lid to the pail the pin D is passed into the perforation a, after which the end of the loop B is passed through the slot b into the casing e, when the same is caught by the lock-hook e, when the key f is turned, thus securing the loop and cup to the pail, and thereby preventing the cover from removal until the ear is again unlocked.

In securing the lid to the pail, as shown in Fig. 2, the pin D is passed into the perforation a, in a similar manner as in Fig. 1, after which the end m of the loop P is sprung through the slot b in the hinge-ear R, the elasticity of the bail N permitting said ear to move outwardly and give to the pressure of the loop, 70 when an ordinary padlock or a pin may be applied through the end of the loop projecting through the slot b, thus securing the cover to the pail.

Having described our invention, what we 80 claim as new, and desire to secure by Letters Patent, is—

1. A bail-ear and lock combination, substantially as described, and for the purpose set forth.

2. A bail-ear hinged at its lower end to the pail, and provided at its upper end with an eye to receive the hook end of a bail, and having a slot below said eye to receive a loop or staple secured to the cup-handle, whereby the 90 same may be locked to the bail-ear, substantially as described.

3. In combination with the bail-ear having the slot b and hook e, the loop B, hinged to the cup-handle, whereby the cup and cover or lid are secured to the pail, substantially as described.

4. The combination of the hinged ear, having the slot b and perforation d', with the wire loop B, pin D, bail N, stationary ear K, having the perforation a to receive said pin, and an eye, f', to receive the hook end of the bail N, substantially as described, and for the purposes specified.

ISAAC M. ROSS,
J. W. ROSS.
